[57] CLAIM

The ornamental design for an organizer for assorted desk articles, as shown and described.

DESCRIPTION

FIG. 1 is a top plan view of an organizer for assorted desk articles showing my new design;

FIG. 2 is a right side elevational view, the left side being a mirror image thereof;

FIG. 3 is a front elevational view;

FIG. 4 is a bottom plan view;

FIG. 5 is a rear elevational view;

FIG. 6 is a perspective view thereof;

FIG. 7 is a top plan view of a second embodiment of my new design of FIG. 1;

FIG. 8 is a right side elevational view of FIG. 7, the left side being a mirror image thereof;

FIG. 9 is a front elevational view of FIG. 7;

FIG. 10 is a rear elevational view of FIG. 7; and,

FIG. 11 is a perspective view of FIG. 7.
